CLAIM

The ornamental design for a flexible elongate member with a portion configured to receive a bone anchor, as shown and described.

DESCRIPTION

This application which is related to U.S. patent application Ser. No. 13/804,407 entitled “Apparatus for Spinal Fixation and Methods of Use,” filed on Mar. 14, 2013, the disclosures of each are incorporated herein by reference in their entireties.

FIG. 1 is a perspective view of a flexible elongate member with a portion configured to receive a bone anchor, showing our new design;

FIG. 2 is a top view thereof;

FIG. 3 is a bottom view thereof;

FIG. 4 is a side view thereof, the opposite side view being a mirror image;

FIG. 5 is a rear view thereof;

FIG. 6 is a front view thereof; and,

FIG. 7 is a cross-section view taken along line 7-7 in FIG. 2.

The dot-dash-dot lines form the bounds of the claimed design and are not part of the claimed design. The diagonal lines in the cross-section do not form part of the claimed design.
